UNITED STATES PATENT OFFICE.

SYLVESTER H. JONES, OF RICHMOND, INDIANA, ASSIGNOR TO THE HOOSIER DRILL COMPANY, OF INDIANA.

CORN-PLANTER.

SPECIFICATION forming part of Letters Patent No. 561,791, dated June 9, 1896.

Application filed February 8, 1896. Serial No. 578,520. (No model.)

To all whom it may concern:

Be it known that I, SYLVESTER H. JONES, residing at Richmond, in the county of Wayne and State of Indiana, have invented certain new and useful Improvements in Corn-Planters, of which the following is a specification.

My invention relates to a corn-planter. One of its objects is to provide improved means for removing the seed-feeding disk from the seedbox without taking the same to pieces.

Another object of my invention is to provide improved means for changing the speed of said feeding-disk, and also for throwing the same out of gear to stop the feed; also, certain details of construction, all of which will be more fully set forth in the description of the accompanying drawings, forming a part of this specification, in which—

Figure 1 represents a side elevation of my device. Fig. 2 is a top plan view. Fig. 3 is an enlarged view of Fig. 2 with seedbox removed. Fig. 4 is a detail view of the shifting-lever. Fig. 5 is a top plan view of the seedbox detached. Fig. 6 is a bottom plan view of the same. Fig. 7 is a central section of Fig. 5. Fig. 8 is a top plan view of the gear-plate for driving the seed-disk. Fig. 9 is a plan view of the feeding-disk. Fig. 10 is a plan view of a detachable slide, which enables the feeding-disk to be removed from the seedbox. Fig. 11 is a bottom plan view of the frame-piece on which the seedbox is mounted.

A represents the side frames of the machine. B represents the pilot-wheel; C, the handle-bars; D, the seedbox; E, the shifting-lever for stopping, starting, and changing the speed of the feeding-disk.

It is often desirable to change the feeding-disk located at the bottom of the seedbox and to replace the same with another disk having a greater or less number of openings. For this purpose I employ a plate 1, having upon its lower face two concentric supporting-gears 2 and 3, with an intervening space between them sufficient to receive the driving-gear c, which meshes alternately with the gears 2 or 3. This plate carries the feeding-disk or dial-plate 7, which is detachably connected thereto as follows: t represents an an-

nular flange formed integral with said plate 1. It is provided with recesses 8 9, which receive the lugs r s of the feed-disk, which makes the engagement between the driving-plate and the seed-plate and causes them to revolve together. The seed-plate 7 is held in position by means of the conical plate 10, bolt 11, and nut 13. The head 12 of the bolt is detachably connected to the boss n of the driving-plate 1 by means of the slotted recesses p, as shown in Fig. 8.

In Fig. 7 the parts are shown secured together in position for use. The seedbox is secured in position by means of anchor-bolts 65 passing through lugs 17 on the seedbox, which rest upon the arms 18, which are formed integral with the stationary plate M and forming a journal-bearing for the stud 6, upon which the gear-plate journals.

19 represents a bolt passing through the seedbox, at one end of the segmental annulus 20, that is formed integral with the stationary plate M, a nut being employed on the end of the said bolt to secure the seedbox at 75 the rear side to the stationary plate M. Now in order to remove the seed-plate it is only necessary to remove the concentric disk 10 and raise the gate 1, which normally rests on the seed-plate, and the feed-disk is removed up through the seedbox and another may be inserted in its place.

I represents a vertically-moving gate secured to the shell of the seedbox by means of bolt 15, passing through the slot in the stem 85 of said gate. It is provided with a knocker-arm J, which is journaled to one ear of said gate and provided with a round point k, which is adapted to enter holes l in the plate a sufficient distance to force the seed through. 90

The feed-disk is rotated by means of a bevel-gear a, engaging with gear-teeth on the pilot-wheel B and transmitting motion through shaft b to gear c, beneath the seedbox. This gear is shifted forward and backward upon 95 the shaft b by means of a yoke-lever d, the forward end of which is provided with pins to engage with the slots c' in the hub of gear-wheel c, which slides freely on shaft b.

e represents an adjustable link connecting 100 the lever d with the hand-lever E. This lever is pivoted at e' to one of the frame-pieces, and

its upper end is provided with a pin *f* to engage with one of either of three holes *g* in the bracket *g'*, thereby holding the lever in the adjusted position. When the pin *f* is in the central opening, the gear *c* occupies the space between the gears 2 and 3, and the feed-disk remains stationary. If it is desired to revolve the disk rapidly, the operator throws the hand-lever *E* to the left in Fig. 1, thereby bringing the gear *c* into engagement with gear 2. If it is desired to revolve the disk slow, the hand-lever *E* is thrown in the opposite direction, and the gear *c* is brought into engagement with the gear 3.

15 16 represents an orifice in the bottom of the seedbox, through which the grain is dropped so as to fall into the seed-tube *F*, down which it passes into the ground.

17 *G* represents a cast frame-piece which is clamped between the side frames *A* and provided with suitable raised bosses *h*, to which the seedbox is secured by means of ears *i*. Plate *G* is also provided with a depressed central portion, forming, in connection with the seedbox, a housing for the gear *c*, and upon the under face it is provided with suitable bosses to receive and support the seed-tube and colter-guard. This supporting-plate *G* thus supports the seedbox and its self-contained dropping devices and also the seed-spout and colter-guard, making a very rigid construction and holding the parts in proper relation, at the same time being a cheap and convenient mode of assembling the parts together.

35 I claim—

1. The combination with the seedbox *D*, of the stationary supporting-plate *M*, the gear-supporting plate 1 provided on its under side with concentric gears 2, 3 and having on its top the annular flange *t* and recessed boss *n* provided with slot *p*, the feed-disk 7 connected with said gear-plate, conical plate 10, bolt 11 having its head 12 detachably engaged in the slotted and recessed boss of the gear-plate, the nut 13, and a driving-gear *c* movable into engagement with either of the gears 2 and 3 or to an inoperative position between said gears, substantially as described.

40 2. The combination with the seedbox *D*

and stationary plate *M*, of the gear-supporting plate 1 provided on its under side with concentric gears 2, 3 and having on its top the annular flange *t* provided with recesses 8, 55 9, the feed-disk 7 having lugs *r*, *s* engaged in said recesses, the conical plate 10 detachably bolted to the gear-supporting plate 1, and the driving-gear *c* movable into engagement with either of the concentric gears 2 and 3 or to an inoperative position between said gears, substantially as described.

3. The combination of the seedbox *D* having lugs 17, the stationary plate *M* provided with arms 18 to which said lugs of the seedbox are bolted, the gear-supporting plate 1 provided on its under side with journal 6 and concentric gears 2, 3, the feed-disk 7 connected with and carried by said gear-plate, and the driving-gear *c* movable into engagement with either of the concentric gears 2 65 and 3 or to an inoperative position between said gears, substantially as described.

4. The combination of the stationary supporting-plate *M* provided with segment 20, 75 the seedbox *D* bolted to said plate and segment, the seed-tube *F*, the rotary feed-disk 7 provided with openings *l*, the vertically-adjustable gate *I*, and the weighted knocker-arm *J* pivoted to said gate and provided with point *k* to engage the openings of the feed-disk, substantially as described.

5. The combination of the seedbox *D* having the supporting-plate *M*, the gear-plate 1 journaled in the plate *M* and provided with 85 concentric gears 2 and 3, the feed-disk 7 detachably connected to said gear-plate, the pilot-wheel *B*, the shaft *b* geared with said wheel, the gear *c* carried by said shaft and movable thereon to engage either of the gears 90 2 and 3 or to occupy an inoperative position between said gears, the yoke-lever *d*, link *e*, lever *E* provided with pin *f*, and the bracket *g'* provided with series of holes *g* to receive said pin and lock the gear *c* in either of its adjusted positions, substantially as described.

95 In testimony whereof I have hereunto set my hand.

SYLVESTER H. JONES.
